[57] CLAIM

The ornamental design for an impact wrench, as shown.

DESCRIPTION

FIG. 1 is a top, front perspective view of the impact wrench showing my new design;

FIG. 2 is a bottom, rear perspective view thereof;

FIG. 3 is an enlarged perspective view of the torqueing portion thereof, the remainder of the wrench being omitted for clarity of disclosure;

FIG. 4 is an enlarged opposite perspective view of the torqueing portion thereof, the remainder of the wrench being omitted for clarity of disclosure;

FIG. 5 is an enlarged perspective view of the handle portion thereof, the remainder of the wrench being omitted for clarity of disclosure;

FIG. 6 is an enlarged opposite perspective view of the handle portion thereof, the remainder of the wrench being omitted for clarity of disclosure;

FIG. 7 is a perspective view of the central portion thereof, the remainder of the wrench being omitted for clarity of disclosure.

FIG. 1
